SIZING BROACH

Wilrose J. Phaneuf, Hudson, Mass., assignor to
The Lapointe Machine Tool Company, Hudson,
Mass., a corporation of Maine

Application February 21, 1941, Serial No. 380,055

4 Claims. (Cl. 90—28.1)

This invention relates to a broach for sizing the bore or inside diameter of a spirally grooved hole, such as the barrel of a pistol, rifle or other firearm.

It is the general object of my invention to provide a sizing broach for previously grooved work which has means to produce a lead or twist of the broach relative to the work during the sizing operation, corresponding to the lead or twist of the previously formed grooves.

To the accomplishment of this object, I provide one or more pilot sections in my improved broach in addition to the broaching sections, and each of these pilot sections is provided with spiral ribs or projections fitting the grooves already formed in the work and of the same lead or twist.

My invention further relates to arrangements and combinations of parts which will be hereinafter described and more particularly pointed out in the appended claims.

A preferred form of the invention is shown in the drawing, in which

Fig. 1 is a side elevation of my improved broach, partially broken away;

Fig. 2 is a transverse sectional view, taken along any one of the lines 2—2 in Fig. 1;

Fig. 3 is a transverse sectional view, taken along the line 3—3 in Fig. 1; and

Fig. 4 is a sectional view of a piece of work which illustrates the intended use of my invention.

Referring to Fig. 1, my improved broach comprises a shank portion 10 by which the broach is pulled through the work, a pilot section 11, a broaching section 12 having a series of broaching members 13, a second pilot section 14, a second broaching section 15 having additional broaching members 16, a third pilot section 17, and a rear end portion 18.

The pilot sections 11, 14 and 17 are substantially identical, except that the section 17 may be of reduced axial length. Each pilot section comprises a series of spiral ribs 20 adapted to fit the spiral grooves 21 (Fig. 4) previously formed in a firearm barrel B or other similar piece of work to be sized. A circumferential groove or recess 22 may be formed at the middle of each pilot section for clearance purposes.

The broaching members 13 and 16 are each of full circular configuration and they increase slightly but progressively in diameter through the first cutting section 12 and also, if desired, through the first part of the second cutting section 15.

The remaining broaching members 16 in the second broaching section 15 will be of the full diameter of the desired bore and are effective to accurately size and smoothly finish the inner surface or bore of the barrel.

In using my improved broach, the work is preferably mounted in a rotatable work holder having anti-friction thrust bearings, so that the work may be free to turn as the broach is drawn through the grooved or rifled opening therein.

Successive pilot sections 11, 14 and 17 are provided, so that some part of one or more pilot sections will always be in the grooves of the work during a broaching operation.

With this construction, the broaching members 13 and 16 move through the work with the same relative lead or twist as the tool which produced the original grooves 21. The bore is sized by removal of successive slight increments of stock between the grooves 21, as indicated at 22 in Fig. 4. The broach is centered in the bore by the spiral ribs on the pilot sections.

In drawing a broach or other cutting tool through a piece of work, it is unavoidable that slight tool marks will be produced in the finished surface. But with my improved broach all such marks in the inner surface or bore will be parallel to the lead or twist of the grooves 21, rather than parallel to the axis of the work.

Consequently, when a bullet or other projectile is fired through a barrel, as B, any tool marks appearing on the inner surface will be parallel to the twisting forward movement of the projectile, so that said marks will not retard the travel of the projectile but will have a tendency to additionally guide the projectile in its desired twisting or rotating forward movement.

Having thus described my invention and the advantages thereof, I do not wish to be limited to the details herein disclosed, otherwise than as set forth in the claims, but what I claim is:

1. A broach for reaming and sizing the inner surface of a spirally grooved hole which comprises a pilot section having spiral ribs fitting the grooves in said hole and of corresponding twist, and a plurality of successively operative circular broaching members having continuous peripheral cutting edges and progressively increasing in diameter and effective to size and smooth the inner cylindrical surface of said hole, said circular broaching members receiving a twisting movement from said pilot section as the broach is drawn through the previously grooved hole.
2. A broach for reaming and sizing the inner

surface of a spirally grooved hole which comprises spaced pilot sections each having spiral ribs fitting the grooves in said hole and of corresponding twist, and a plurality of successively operative circular broaching members having continuous peripheral cutting edges and progressively increasing in diameter and interposed between said pilot sections, said circular broaching member being effective to size and smooth the inner cylindrical surface of said hole and receiving a twisting movement from said pilot sections as the broach is drawn through the previously grooved hole.

3. The combination in a reaming and sizing broach as set forth in claim 2, in which a series

of additional circular broaching members are provided which follow the second pilot section and which additionally size and smooth said inner surface.

5 4. The combination in a reaming and sizing broach as set forth in claim 2, in which a series of additional circular broaching members are provided which follow the second pilot section and additionally size and smooth said inner surface, and in which an additional ribbed pilot section is provided which follows the second broaching section and maintains the relative twist of the broach during completion of the sizing operation.
